METHOD FOR CONTROL OF PARAFFIN DEPOSITION

Donald L. Andersen, Minneapolis, and Jean B. Thielen, St. Paul, Minn., assignors to General Mills, Inc., a corporation of Delaware

No Drawing. Filed Sept. 19, 1960, Ser. No. 56,673
8 Claims. (Cl. 252—8.3)

The present invention relates to a method for preventing the deposition in oil well production equipment, etc. of the paraffin-like solid hydrocarbon materials contained in petrolierous fluids. More particularly, the present invention relates to the use of chemical compounds, as paraffin deposition inhibiting agents.

The problem of "paraffin" deposition has been one of long standing in many phases of the oil industry. The so-called "paraffin" deposition occurs in flow lines, in pumping rods, tubing, and at other points which come in contact with the crude oil. The term "paraffin" as used in this context by those skilled in the art, refers to any material which is insoluble or undispersible in crude oil under conditions of production. Thus, the "paraffin" deposit may contain high molecular weight aliphatic hydrocarbons (straight and branched chains), resins, asphaltic materials, aromatic hydrocarbons, naphthalene, oil, inorganic scale, water and sand. As will be understood, of course, the composition of such a deposit varies from one crude oil type to another, from one well to another in the same area, and from one geographic location to another.

In the past a great variety of treatments have been used to prevent the deposition of paraffin. One of the more common methods has been the physical treatment using scraping devices and heating devices. Chemical solvents have also been used to remove deposits. In fact, some solvent formulations were developed that will react in part with the well fluid to produce heat in addition to the solvent action. Still other chemical formulations were used to form a soluble "plug" which has both mechanical and solvent functions. Efforts have even been made to plastic coat and otherwise treat pipes to prevent deposition. In some instances even combinations of all these methods have been used, but the problem still remains.

The various methods each have their disadvantages. The mechanical cleaning or scraping of pipes has proven to be too expensive for wide spread adoption. Many of the chemical solvents proposed cause handling and toxicity problems and similarly the treating and plastic coating of piping has not proven economical or practical.

It is therefore an object of the present invention to provide a novel method of preventing, controlling, or removing paraffin deposits in oil well production equipment. It is another object of the present invention to provide a safe, economic, continuous method of preventing the deposition of paraffin. Other objects will appear herein after.

It has now been discovered that compounds of the formula

in which R is an aliphatic hydrocarbon group having 8 to 22 carbon atoms, A is a divalent hydrocarbon radical having 1 to 6 carbon atoms, X is a member selected from the group consisting of hydrogen, an alkali metal, and an amine, and m is 0 to 1, effectively prevent the deposition of "paraffins" when added to the crude oil.

Representative of the compounds contemplated for use in the present invention are the detergent amino acids such as N-alkyl-β-aminopropionic acid, N-alkyl-β-aminocrotonic acid, N-alkyl-β-aminobis-propionic acid, N-alkyl-β-aminobis-crotonic acid; the alkali metal and amine salts of the detergent amino acids; the zwitterion form of the detergent amino acids; and the ethoxylated, sulfonated,

2

methylated, quaternized derivatives of these acids. The structures of some of the preferred compounds are:

5 Disodium N-tallow-β,β-amino dipropionate where R is a tallow fatty radical;

N-coco-β-amino-propionic acid where R is a coco fatty radical;

10 N'-tallow propylene diamine salt of N-coco-β-amino-propionic acid, where R is coco and R' is tallow;

15 triethanolamine salt of N-coco-β-amino-propionic acid where R is coco; and

20 N'alkylamino-N-tallow-β-amino-propionamide where R=tallow and R' is alkyl such as tallow, octyl, or methyl.

Many of the above-described compounds are commercially available while others can be prepared by a variety of well known chemical reactions. The acid form of the compound is formed by simply reacting a primary alkyl amine with an unsaturated acid such as crotonic acid, etc. or by reacting a primary alkyl amine with a lower alkyl ester of an unsaturated acid in the manner described in U.S. Patent 2,468,012 and then hydrolyzing the ester to the corresponding acid. The salts of the detergent amino acids are readily formed by conventional methods, whereas, the zwitterion form of the detergent amino acid is obtained by adding a non-oxidizing acid to the alkali metal salt as described in U.S. Patent 2,816,920. The various ethoxylated, sulfonated, methylated and quaternized derivatives are likewise prepared by conventional methods.

25 While single isolated primary amines are used with excellent results in preparing the above-described compounds, the mixture of amines obtained by the amination of the mixed fatty acids or selected fractions thereof present in common fats and oils are preferred because of their availability. Typical of such amines are "coco" amine which contains fatty groups of from 8 to 18 carbon atoms and "tallow" amine which contains fatty groups of from 8 to 22 carbon atoms and which are obtained by the amination of the fatty acids or fractions thereof found in coconut oil and tallow, respectively.

30 In the practice of the present invention the amount of fluidizing agent to be employed is not critical and will vary with the nature of the petrolierous liquid encountered. In general, however, it can be said that satisfactory results are obtained when .01 to 1% of the agent, by weight of the paraffin content, is employed. Of course, when treating paraffin deposits which already exist, larger amounts of the agent may be advantageously employed. In either event the determination of optimum amount of agent to be employed is best determined by trial.

35 The present invention is further illustrated by reference to the following examples. Unless otherwise indicated all parts and percentages used herein are by weight.

40 The effectiveness of a paraffin inhibitor is best evaluated by the laboratory test procedure set forth below.

45 Various paraffin inhibitors to be tested were weighed into 50 cc. centrifuge tubes, 30 g. of the paraffin-containing crude oil was added and the contents thoroughly mixed by vigorously shaking the tube by hand. The centrifuge tube was placed in a model W2-801 centrifuge made by International Clinical Centrifuge Company and centrifuged for 5 minutes. The centrifuge tubes were removed from the centrifuge and the supernatant liquid decanted. The par-

affin precipitate was compared to a control sample which was subjected to the same treatment in the absence of an inhibitor. The results of this testing is shown in Table I. Some of the solid materials are more conveniently added to the crude oil as solutions. If a solvent was used it is listed in the third column of Table I. Following the solvent is the ratio of solvent to inhibitor in the solution.

sition inhibiting agent is disodium N-tallow- β,β -iminodipropionate.

3. The method of claim 1 wherein the paraffin deposition inhibiting agent is N-coco- β -aminopropionic acid.

4. The method of claim 1 wherein the paraffin deposition inhibiting agent is N-tallow propylene diamine salt of N-coco- β -aminopropionic acid.

Table I

Example	Inhibitor	Inhibitor solvent	Inhibitor concentration, percent	Paraffin concentration, percent	Description of results
1	Disodium N-tallow- β,β -amino-dipropionate.	water (6:1)	0.3	10	Precipitate was approximately the same volume as the control, but the precipitate was quite fluid and pourable.
2	do	none	0.5	20	Volume of precipitate reduced 50%.
3	N-coco- β -amino-propionic acid	kerosene (1:1)	0.5	10	Do.
4	do	do	0.5	20	Do.
5	N'-tallow propylene diamine salt of N-coco- β -amino-propionic acid.	none	0.5	10	Do.
6	Triethanolamine salt of N-coco- β -amino-propionic acid.	do	0.3	25	Do.
7	N-tallow- β -amino-propionic acid	kerosene	0.3	10	Volume of precipitate reduced 25%.
8	Methyl-N-tallow- β -amino propionate	none	0.5	10	Do.
9	N'-alkylamino-N-tallow- β -amino-propionamide where the alkyl is 8 and 10 carbon straight chain.	xylene (3:2)	0.8	10	Volume of precipitate reduced 50%.
10	N'-tallow amino-N-tallow- β -amino-propionamide.	do	0.8	10	Do.

As clearly demonstrated, the inhibitor sharply reduces the deposition even under the unusually severe conditions of this test.

The foregoing examples are intended as illustrations of preferred embodiments of the present invention and are not to be interpreted as limitations on the scope thereof.

The embodiments of the invention in which an exclusive property or privilege is claimed are defined as follows:

1. The method of preventing the deposition of paraffin contained in petrolierous fluids which comprises adding to said fluids a paraffin deposition inhibiting agent of the formula:

in which R is an aliphatic hydrocarbon group having 8 to 22 carbon atoms, A is a divalent hydrocarbon radical having 1 to 6 carbon atoms, X is a member selected from the group consisting of hydrogen an alkali metal and an amine; and m is 0 to 1.

2. The method of claim 1 wherein the paraffin depo-

5. The method of claim 1 wherein the paraffin deposition inhibiting agent is the triethanol amine salt of N-coco- β -amino propionic acid.

6. The method of claim 1 wherein the paraffin deposition inhibiting agent is N-tallow- β -aminopropionic acid.

7. The method of claim 1 wherein the paraffin deposition inhibiting agent is N'-alkylamino-N-tallow- β -amino-propionamide.

8. The method of claim 1 wherein the paraffin deposition inhibiting agent is methyl-N-tallow- β -amino-propionate.
